(57) **CLAIM**

The ornamental design for a rifle stock retaining bracket, as shown and described.

DESCRIPTION

FIG. 1 is a perspective view of the rifle stock retaining bracket of the present invention;

FIG. 2 is a top plan view of the rifle stock retaining bracket;

FIG. 3 is a side view of the rifle stock retaining bracket as seen from the left side;

FIG. 4 is a bottom plan view of the rifle stock retaining bracket;

FIG. 5 is a side view of the rifle stock retaining bracket as seen from the right side;

FIG. 6 is a rear view of the rifle stock retaining bracket;

FIG. 7 is a front view of the rifle stock retaining bracket; and,

FIG. 8 is a right side view of the rifle stock retaining bracket shown in its environment mounted to an AR-15 style rifle. The broken lines are for illustrative purposes only and form no part of the claimed design.
